UNITED STATES PATENT OFFICE

WILLIAM A. MOELLER, OF LOS ANGELES, CALIFORNIA, ASSIGNOR TO THE LOS ANGELES SPRING BED COMPANY, OF LOS ANGELES, CALIFORNIA

FOLDING BED

Application filed February 28, 1927. Serial No. 171,502.

This invention has to do with a folding bed and has particular reference to a bed of the type known, generally, as a day bed. It is a general object of my present invention to provide a folding bed of the type mentioned, which is simple of construction, practical and simple to operate.

It is a primary object of my present invention to provide a folding bed including two bed frames connected so that one is operated by or from the other so that a person can operate the bed easily and without great exertion.

Another object of my present invention is to provide a simple, effective and practical mechanism for interconnecting the frames of a day bed, or the like.

Another object of my invention is to provide a bed of the type mentioned having ample space for bedding when the parts are collapsed or folded.

It is another object of my invention to provide a bed of the type mentioned which operates freely and easily without the aid of spring counterbalances, or the like.

The various objects and features of my invention will be best and more fully understood from the following detailed description of a typical form and application of the invention, throughout which description reference is had to the accompanying drawings, in which:

Fig. 1 is a sectional view of the bed provided by my invention, showing it in folded or collapsed position and showing the inner bed frame indicated in dotted lines to avoid confusion;

Fig. 2 is a sectional view of the construction, showing the bed open or an extended position;

Fig. 3 is a front elevation of a part of the bed with the parts in the folded position, being a view taken as indicated by line 3-3 on Fig. 1; and

Fig. 4 is an enlarged, detail, sectional

view, taken as indicated by line 4-4 on Fig. 1.

The construction provided by my invention includes, generally, a base 10, an inner bed frame 11, an outer bed frame 12, a mounting 13 for the inner bed frame, a mounting 14 for the outer bed frame, and means 15 connecting the mountings whereby the frames operate together.

The base 10 is preferably a rectangular structure including a back 16, a front 17 and ends 18. It is to be understood that the base may be constructed of wood, metal, or any other suitable material, and that it may be made of any suitable design or may be ornamented or decorated in any suitable manner. In the drawings, I have shown a base construction in which the ends 18 include metal plates 18a which extend between and connect the front and back, and outer parts 18b which connect to the outer sides of the plates. The outer parts 18b may be decorated or finished in any suitable manner. The base 10 is proportioned to receive or hold the inner bed frame 11 so that the frame 11 is movable vertically in the base between a down position, as indicated in dotted lines in Fig. 1, and an up position, as shown in Fig. 2. Further, the base is designed to receive and support the outer frame 12 when the bed is in the folded position, as shown in Fig. 1.

The bed frame 11 is preferably a rectangular frame, formed of angle iron, or the like, made to suitably fit within the base 10. In practice, I may provide vertical guides 20 in the corners of the base 10 to guide the corners of the frame 11 as it is moved vertically in the base. Further, I may provide stops or rests 21 in the base 10 to receive and support the frame 11 in its down position, as shown in Fig. 1.

In accordance with my invention, the mountings for the frames and the parts connected therewith are provided at the two ends 90

of the structure. The construction at the two ends of the structure being the same, I will describe in detail the parts at one end, it being understood that such description applies 5 also to the other end.

The mounting 13 for the bed frame 11, whereby the frame is connected in the base, includes, generally, two bellcranks A and B and a connection between the bellcranks 10 whereby they operate together. In the preferred arrangement, the two bellcranks are mounted on the plate 18a at the end of the base. The bellcranks have long arms 22 which carry the frame 11, and short arms 23, 15 which are connected together by links 24 and 25. The bellcranks are mounted by means of pivot pins 26 in suitable spaced relation on the plate so that their long arms engage the frame 11 to operate it vertically. In the operation of the bed, the bellcranks move 20 between the positions shown in Fig. 1 and those shown in Fig. 2 and, in thus moving, the outer ends of the long arms 22 swing or have an arcuate movement. The frame 11 moves 25 straight up and down. Therefore, it is necessary to provide a sliding connection between the outer ends of the arms 22 and the frame 11. In the drawings, I have shown 30 rollers 26a mounted on the outer ends of the arms 22 and I have shown suitable brackets 27 on the frame 11, which receive and hold the frame 11 on the rollers allowing the rollers to move the necessary amount horizontally 35 relative to the frame. The links 24 and 25 are connected by pivot pins 28 to the outer ends of the short arms 23 and are pivotally connected together by a pivot pin 29. This link connection between the bellcranks causes 40 them to operate together or in unison when the bed is actuated as will be hereinafter described.

The mounting 14 provided for the outer frame 12 includes two links 30 and 31 pivotally connected to the frame 12 and to the end 45 plate 18a of the base 10. The foremost link 30 is pivotally connected with the frame 12 by a pin 32 and may be pivotally connected with the plate 18a by the pivot pin 26 which connects the foremost bellcrank A with 50 the plate 18a. The inner or rear link 31 is pivotally connected with the frame 12 by a pin 33 and is pivotally connected by a pin 34 with the plate 18a at a point intermediate the two bellcranks. The link 30 is prefer- 55 ably arranged between the bellcrank A and the plate 18a, and is provided with an extension 30a so that it has an effective bearing on the plate 18a and is, therefore, effective in holding the frame 12 steady during operation of the bed. The links 30 and 31 are 60 proportioned so that the frame 12 can be swung between an in or folded position, where it is supported on the base, and an out or extended position where it projects forward 65 from the base and is in a horizontal position

in substantial horizontal alignment with the inner frame 11 when the inner frame is in its up position. Notches or openings 60 are provided in the base at the point of junction 70 of the front and end parts 18b. These openings pass or receive the links 30 and 31 when the bed is extended, as shown in Fig. 2 of the drawings. In practice, the frame 12 may be a rectangular frame formed of angle iron, 75 or the like, and when forming the frame of angle iron, the angle iron may be faced outwardly so that it has flange parts 35 which overhang or rest on the back and end parts 18b of the base when the frame is in the in position, as shown in Fig. 1.

Legs 37 may be provided on the forward end of the frame 12 to support the outer end of the frame 12 when the frame is in the extended position, as shown in Fig. 2. The legs are preferably designed and proportioned to cover the openings 60 in the base when the bed is folded, as shown in Fig. 1.

The connection between the mountings whereby the two frames operate together in the desired manner includes an arm 40, extending or projecting from the end of the link 31 beyond the pivot pin 34, and a yoke or notch at the end of the link 25 to receive the end of the arm 40. In practice, I provide a pin or projection 42 on the outer end of the arm 40 to fit or cooperate with the notch 80 in the end of the link 25. In accordance with my present invention, the arm 40 is spaced from or is out of co-operative engagement with the link 25 when the outer frame 12 is in the in position, as shown in Fig. 1, and does not engage the link 25 until the outer frame 12 has been lifted and swung forward to a position where it is ready to be lowered to its operating position, as shown in Fig. 2. After the projection 42 on the arm 40 engages the link 25, lowering of the outer frame to its extended position causes operation of the link 25 in a manner to swing the bellcranks between the position shown in Fig. 1 and that shown in Fig. 2, which operation causes the inner frame to be lifted from the position indicated in Fig. 1 to the position shown in Fig. 2. With this arrangement, the weight of the outer frame counter-balances the weight of the inner frame, making the bed open very easily. Likewise, when the bed is being closed, the inner frame lowers as the outer frame is lifted and, therefore, counter-balances the outer frame.

I may provide stops 61 and 62 to stop the bellcranks A and B in the down position, as shown in Fig. 1. Further, I may provide stops 63 and 64 to receive the links 24 and 25 in the down position, shown in Fig. 1. In practice, I provide some looseness in the connection between the links 24 and 25 to allow for proper operation by the arm 40. Further, I may curve the link 24, as shown in the 130

drawings, so that it will not interfere with the pin 42 on the end of the arm 40.

It will be obvious that the frames 11 and 12 may be equipped with suitable springs 70 and coverings 71 so that the extended structure forms a comfortable bed. With my construction, I can obtain a substantial space between the frames in the folded position to carry bed clothing.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A bed of the character described including, a base, an inner frame, bell cranks mounting the inner frame in the base to be movable vertically, members pivotally connected with the cranks and pivotally connected together whereby the cranks operate together, an outer bed frame, a link connecting the outer frame with the base whereby the outer frame is movable up and forward from the base to an up position and then downward and forward from the up position to a position at the front of the base, and an arm on the link co-operating directly with one of the said members when the outer frame is operated between the up position and the position at the front of the base whereby the frames operate together during the downward and forward movement of the outer frame.

2. A bed of the character described including, a base, an inner frame, bell cranks mounting the inner frame in the base to be movable vertically, members pivotally connected with the cranks and pivotally connected together whereby the cranks operate together, one of the members having a notched part, an outer frame, a link connecting the outer frame with the base whereby the outer frame is movable up and forward from the base to an up position and then downward and forward from the up position to a position forward of the base, and an arm on the link to co-operate with said notched part when the outer frame is moved downward and forward whereby the frames move together during operation of the outer frame between the up position and the position at the front of the base.

3. A bed of the character described including, a base, an inner frame, bell cranks mounting the inner frame in the base to be movable vertically, members pivotally connected with the cranks and pivotally connected together whereby the cranks operate together, fixed stops positioned to limit movement of said members, an outer frame, a link connecting the outer frame with the base whereby the outer frame is movable up and forward

from the base to an up position and then downward and forward from the up position to a position at the front of the base, and an arm on the link to co-operate with one of said members during the operation of the outer frame between the up position and the position at the front of the base whereby the frames operate together during operation of the outer frame between the up position and the position at the front of the base.

In witness that I claim the foregoing I have hereunto subscribed my name this 21st day of February, 1927.

WILLIAM A. MOELLER.
